Patented Feb. 2, 1926.

1,571,874

UNITED STATES PATENT OFFICE.

ALBERT C. FISCHER, OF CHICAGO, ILLINOIS.

EXPANSION JOINT.

No Drawing.

Application filed September 11, 1922. Serial No. 587,611.

To all whom it may concern:

Be it known that I, ALBERT C. FISCHER, a citizen of the United States, residing in Chicago, county of Cook, State of Illinois, 5 have invented a certain new and useful Improvement in Expansion Joints.

My invention relates to a mixture of bituminous matter containing corn cob fibres as distinguished from the old art in which 10 hemp-flax-linters, oakum, felt, and even sawdust were incorporated as is well known to those versed in the art.

I find the chaffy, fibrous nature of the corn cob, when ground, to be well suited for the 15 purpose herein disclosed, namely, constructing expansion joints to take up expansion and contraction in concrete roads, buildings, etc. The ground corn cob is incorporated in the bituminous matter in about the same 20 volumetric proportion as the above-mentioned fibrous matters have generally been employed, the asphalt being, of course, warmed to a temperature which will permit it to be kneaded or stirred sufficiently to in- 25 corporate the ground corn cob therewith, for instance, as described in my previously filed application of May 10, 1922, Serial No. 559,908, covering the improvements in ex- 30 pansion joints, according to which fibrous matter and other like substances, such as excelsior, are incorporated in a bituminous mixture while the bituminous material is merely plastic as distinguished from fluid

and therefore lacking in penetration power; or, if preferred, the mixing may be carried on in accordance with the common practice where fibrous matters, as hereinbefore pointed out, have previously been used in making expansion joints. 35

Sawdust is objectionable because of its 40 rosinous content, and fibrous matter such as hemp, flax, linters and feltings are exceedingly expensive when compared to the cost of fibrous matter secured from the corn cob; likewise, the flat, chaffy fibre is quite strong 45 and because of its flattened nature has greater binding power than the rounded lighter structures of fibre secured from linters, feltings, hemp, flax, etc.

The bituminous matter may be cellular or 50 solid, as desired.

If the bituminous matter is to be developed in cellular structure or form, this can be accomplished by following the teachings of my Letters Patent No. 1,401,974, granted 55 January 3, 1922, for sponge asphalt.

I claim:

1. Bituminous expansion joints having incorporated therein corn cob fibre.
2. Cellular bituminous expansion joints 60 having incorporated therein corn cob fibres.
3. Bituminous expansion joints having incorporated therein ground corn cob.

Signed at Chicago, Illinois, this 9th day of September, A. D. 1922.

ALBERT C. FISCHER.
